UNITED STATES PATENT OFFICE.

HARVEY H. HALL, OF DENVER, COLORADO, ASSIGNOR TO THE IDEAL DISAPPEARING WALL BED COMPANY, OF DENVER, COLORADO, A CORPORATION OF COLORADO.

DISAPPEARING WALL-BED.

1,060,753.

Specification of Letters Patent.

Patented May 6, 1913.

Application filed December 9, 1912. Serial No. 735,806.

To all whom it may concern:

Be it known that I, HARVEY H. HALL, a citizen of the United States, residing at Denver, in the county of Denver, State of Colorado, have invented certain new and useful Improvements in Disappearing Wall-Beds; and I do hereby declare the following to be a full, clear, and exact description of the invention, such as will enable others skilled in the art to which it appertains to make and use the same.

This invention relates to improvements in folding beds, and more particularly to that type known as wardrobe or disappearing wall beds, generally used in apartment houses, where the bed when not in use may be folded out of sight, and the bed room utilized for other purposes.

The primary object of the invention is to provide a bed of this type, which will be more simple in construction, effective in action, and less expensive to manufacture than those heretofore proposed.

To these ends the invention consists in the novel details of construction and combination of parts more fully disclosed in the following specification, and particularly pointed out in the appended claims.

While the invention is not limited to the exact details shown and described, still for the purpose of disclosure, reference is had to the accompanying drawings illustrating a practical embodiment of same, in which drawings like numerals designate the same parts in the several views, and in which—

Figure 1 is a view in perspective of the bed in its open position. Fig. 2 is fragmentary, sectional view taken in the plane of the line 2—2 of Fig. 1. Fig. 3 is a horizontal sectional view taken on the line 3—3 of Fig. 2, and Fig. 4 is a detail diagrammatic elevational view, showing a slightly different arrangement.

A pair of side walls 1 form a compartment for receiving and containing the bed in its folded position, and the side walls may be the sides of a wardrobe or the side walls of a recess formed in the wall of the room. The recess is provided with doors 2 for closing said recess when the bed is folded.

3 is a bed frame having at its outer end a suitable folding foot board 4, the inner end of said bed frame being peculiarly supported as hereinafter described.

55 The foot board or support does not form a part of the present invention, but the

manner of folding same may be briefly referred to.

5 designates a short link on each side of the bed disposed within the channelled rail and connected at one end to the foot board as at 6. The other end is pivoted as at 7 to the inside of the rail. 8 is a longer link on each side of the bed pivotally secured at 9 to the foot board and at 10 to the inside of the rail, so that when the bed, is to be folded the foot board may be swung around underneath same on the pivots 7 and 10.

Suitable weights 11 are mounted on the inner rail 12 of the bed frame.

13 designate guide-ways opposite to each other and located on the inside faces of the side walls. These guideways, which are in the nature of slots, preferably extend on an incline upwardly and inwardly to a position substantially in alinement with the bed frame when opened, or for a height substantially equal to the height of the bed frame.

The upper ends of the guideways may preferably be provided with lateral slots 14, which form a continuation of the upper ends of the inclining guideways, and while they may extend inwardly, are shown extending outwardly from the top thereof, preferably inclining downwardly at a slight angle. On each side rail of the bed, toward the inner end thereof, there is mounted a suitable projection or roller 15 engaging said guideways. These projections or rollers ride in the slots 13, the inclination of which tend to effect a downward thrust on the inner portion 16 of the bed, which assists in elevating the outer or longer portion thereof, and in the reverse direction of movement aids in retarding the lowering of the bed, as will be hereinafter referred to.

A pair of links 17 are pivotally supported at their lower ends, as at 18, and the supports 18 may be secured to the side walls 1, or to the floor as illustrated. The upper ends of this pair of links are pivotally connected to a portion of the bed frame, preferably to the side rails as being the most convenient parts. The links 17 are longer than the distance between the pivotal connection 19 and the rollers 15, so that in any position of inclination of the bed frame above the horizontal, a radius line from 19, and of a length equal to the distance between 19 and 15, will always find a movable

terminal position in the slot 13, preventing any binding of the parts.

In the drawings the upper ends of the links 17, are shown not merely as pivoted to the side rails, but also slidably engaging the same; 20 designating short slots in which the pivots 19 ride. This construction is not essential, as the upper ends of the links 17 may simply be pivoted to the bed frame, but where the short transverse slots or guideways 14 are employed, the slots 20 are provided to enable the bed frame to be slid outwardly, when opened, in order that the inner end may be supported by the guideways or lower faces of the slots 14, against possible downward displacement. From the detail diagrammatic view shown in Fig. 4, however, it will be seen that the slots 14 and 20 are not absolutely essential, because 20 when the bed is in its open position, and with the rollers 15 in the upper ends of the guideways 13, the weight of the inner portion of the bed will tend to force the rollers downwardly in the guideways, and will tend 25 also to cause the links 17 to swing downwardly and outwardly, and as the links and guideways converge downwardly, there is caused a horizontal stress, in opposite directions, on the rollers 15 and the pivots 19, 30 binding the bed against bodily downward displacement at its inner end. This, however, to an extent causes a strain or stress on the pivoted rollers and the pivots 19 of the links 17, which is more or less overcome 35 by the construction illustrated in Fig. 1 where the weight of the inner end of the bed frame is directly supported by the links and the rollers 15 resting in the transverse slots 14, and also preventing the bed from 40 folding up of its own accord should a greater weight be placed on the end 16 by the occupant or otherwise, an objectionable feature that has occurred in certain styles of folding beds, where the pivots 19 are 45 located nearer the center of the bed frame.

Assuming that the bed is in its folded up position the links 17 will be in substantially vertical positions alongside of the bed frame. The inner rail may be transversely slotted 50 to receive the links 17 when they are secured to the inside of the side rails. In this position the rollers 15 are in their lowermost position in the slots 13. Upon pulling out the upper or outer end of the bed the 55 weights 11 will tend to counter-balance the weight of the major portion of the bed, from the pivots 19 to the outer end, and in addition to this the rollers 15 riding up the inclined slots 13, will help to retard the descent of the outer portion of the bed. When 60 the bed is fully lowered the rollers 15 are in the upper ends of the slots 13 opposite the transverse guideways 14. Up to this

point the pivots 19 have rested against the ends 20^a of the slots 20, and upon pulling outwardly upon the bed the pivots 19 ride toward the end 20^b and the rollers 15 ride down the short slots 14 and are supported against displacement by the lower faces of these slots. The slots 14 incline downwardly 70 in order that the frame may not work inwardly unless actually forced back. In housing the bed the parts move in the reverse order, and as the bed is elevated, the walls of the inclined slots 13, engaging the 75 rollers 15, tend to force the inner end 16 of the bed downwardly and outwardly, and thus assist the counterbalancing weights 11 in compensating for the weight of the outer portion of the bed.

While the invention consists of the general construction and arrangement of parts as illustrated it will be obvious that the same is not limited to the exact details of construction, and where I use the term rollers, 85 it will be understood, for instance, that their equivalent, such as pins or pintles may be employed to operate in the inclined slots.

What I do claim is:—

1. The combination of a bed frame; a 90 pair of swinging links slidably connected at one of their ends to said frame; oppositely disposed guideways located adjacent the inner end of said frame and inclining upwardly and inwardly to a position substantially in line with the top of the bed frame when opened, and terminating in laterally disposed short slots; and projections carried by the inner end of said frame, riding in said inclined and transverse guideways and slots, substantially as described.

2. The combination of a bed frame having its inner end weighted; inclosing side walls for said frame; oppositely disposed slots formed on the inside faces of said walls and 105 inclining upwardly and inwardly to a position substantially in line with the top of the bed frame when opened, and terminating in short transverse slots slightly inclined downwardly; a pair of links pivotally supported at their lower ends below said inclined slots and slidably connected at their upper ends with said bed frame; and projections carried by the inner end of said bed frame and operating in said inclined and short slots, the distance from said projections to said sliding connections between the frame and said links, being less than the length of the links, substantially as described.

In testimony whereof, I affix my signature, in presence of two witnesses.

HARVEY H. HALL.
